Frank C. Williams
Attorney

UNITED STATES PATENT OFFICE.

FRANK C. WILLIAMS, OF SALT LAKE CITY, UTAH, ASSIGNOR OF ONE-HALF TO EUGENE GILES, OF SALT LAKE CITY, UTAH.

ATTACHMENT FOR SAFETY RAZORS.

Application filed March 15, 1921. Serial No. 452,511.

To all whom it may concern:

Be it known that I, FRANK C. WILLIAMS, a citizen of the United States, residing at Salt Lake City, in the county of Salt Lake 5 and State of Utah, have invented a new and useful Attachment for Safety Razors, of which the following is a specification.

This invention is a new and useful auxiliary handle for safety razors.

10 The standard safety razors which are now in general use, are usually constructed in such manner that the blade is rigidly held with respect to the handle. This type of construction is open to objection for the reason that it is difficult for any user but the most expert, to shave with them with any degree of comfort. This is because, usually, the blade is drawn over the face with a hoe-like action, which fails to completely sever 15 the beard, and is very irritating to the skin. The best results in shaving with a safety razor, are obtained when the blade is held by the user at such an angle that it will move across the face with a drawing or 20 slicing cut, somewhat parallel with the edge of the blade, which type of cut efficiently removes the beard from the face without irritation. The object of the invention is to provide means by which the blade of a 25 safety razor may be adjusted to any desired angle suited to individual requirements, and retained in the adjusted position, whereby the desired drawing or slicing cut is assured at all times.

30 The invention will be hereinafter fully set forth and particularly pointed out in the claims.

In the accompanying drawing:—

Figure 1 is a perspective view illustrating 35 an auxiliary handle constructed in accordance with the invention, a standard safety razor being conventionally shown in dotted lines. Figure 2 is a top end view illustrating the angular adjustment of the 40 razor. Figure 3 is an end view of the auxiliary handle with the razor removed. Figure 4 is a sectional view illustrating a slight 45 modification.

Referring to Figures 1, 2 and 3 of the 50 drawing, 10 designates the auxiliary handle, which is preferably of approximately elliptical cross section, and is provided with a central longitudinal bore 11, of circular cross section. The upper end of the handle 55 10 is provided with a cut out portion 12 at

one edge, for providing clearance for the head 13, of a set screw 14, which extends through the body of the handle into the bore 11. 15 designates the handle of a standard safety razor, provided with the usual guard 60 and blade conventionally illustrated at 16.

In practice, the handle 15 is inserted into the bore 11, and rotated until the razor blade is at the proper angle to give the desired slicing or draw cut. The set screw 14 is 65 then tightened so as to engage the handle 15 and prevent its rotation. By this means, the razor blade is held at such an angle, that even if the user draws the blade straight down, as many of them do in shaving, the blade will move downwardly and obliquely, in a direction parallel with the edge of the blade, and thereby produce the proper slicing or draw cut.

If desired, a special type of blade holder 75 may be employed in conjunction with the handle 10, as illustrated in Figure 4. In said figure the blade holder 16^a is shown as provided with a central rigid stud 15^a capable of entering the bore 11 and of being 80 engaged by the set screw 13. It is obvious from the drawing that the angle of the blade may be adjusted in the handle 10 in the same manner that the guard 16 (Figure 1) is adjusted.

85 From the foregoing it will be seen that the invention provides an exceedingly simple and convenient means by which a standard safety razor, rigidly secured to its handle, may be adjusted to an angle to suit the requirements of any user, and rigidly maintained at the adjusted angle.

Having thus explained the nature of the invention and described an operative manner of constructing and using the same, although without attempting to set forth all of the forms in which it may be made, or all of the forms of its use, what is claimed is:—

1. An attachment for safety razors comprising an auxiliary handle having a bore 95 capable of loosely receiving the handle of a standard safety razor, and means whereby relative rotation of said handles may be prevented.

100 2. An attachment for safety razors comprising an auxiliary handle having a bore capable of loosely receiving the handle of a standard safety razor, and a set screw carried by said auxiliary handle and positioned to engage the handle inserted in said bore.

3. An attachment for safety razors comprising an auxiliary handle having a bore capable of loosely receiving the handle of a standard safety razor, said auxiliary handle having a cut away portion in its surface contiguous to one end, and a set screw working in the cut away portion and positioned to engage the handle inserted in said bore.
4. An attachment for safety razors comprising an auxiliary handle of approximately elliptical cross section, having a central longitudinal bore of cylindrical cross section capable of loosely receiving the handle of a standard safety razor, and means whereby relative rotation of said handle may be prevented.
5. An attachment for safety razors com-

prising a handle having a bore leading in from one end, a razor provided with a member shaped to enter and rotate within said bore, and means whereby relative rotation of said member and said handle may be prevented.

6. An attachment for safety razors comprising a handle having a bore leading in from one end, a razor provided with a member shaped to enter and rotate within said bore, and a set screw carried by said handle and positioned to engage and rigidly hold said member.

In testimony whereof I have hereunto set my hand.

FRANK C. WILLIAMS.
